DEVICE FOR CURLING HAIR

Charles K. Thau, Brooklyn, N. Y.

Application October 18, 1934, Serial No. 748,778

14 Claims. (Cl. 132—41)

My invention relates to hair curlers and refers particularly to hair curlers adapted for the winding of hair thereon and to be retained in position upon the head until a curl, or wave, is produced thereon.

The device of my invention is so constructed that the ends of the hair are firmly clasped thereon to allow of the winding of the entire hair strand around it, coupled with means for maintaining the hair in wound position and means for preventing the accidental dislodgment of the device from the wound hair.

The advantages of my device will be evident upon a consideration of my specification and its accompanying drawing, in which similar parts are designated by similar numerals.

Figure 1 is a top plan of one form of my device.

Figure 2 is a side view of the device of Figure 1.

Figure 3 is a bottom view of the device of Figure 1.

Figure 4 is an enlarged section on the line 4—4 of Figure 1.

Figure 5 is a section on the line 5—5 of Figure 4.

Figure 6 is a section on the line 6—6 of Figure 4.

Figure 7 is a perspective view of the retaining member and spring member of the device shown in Figures 1, 2, 3 and 4.

Figure 8 is a perspective view of the inner terminal of the clamping member.

Figure 9 is a perspective view of the two extended fixed arms of the device.

Figure 10 is a section similar to Figure 6 taken through a modified form of my device.

The particular form of my device shown in Figures 1 to 9, inclusive consists of a base or supporting member, having the cylindrical side 15 and the end cover 16. The upper face of the base has an elongated slot 17 and the under face thereof having an elongated slot 18.

A locking member 19 is pivotally attached to the base side 15 by means of a pivot 20 and is capable of placement within the slot 18. The free end 21 of the locking member 19 is turned upon itself to form a hook-like terminal which is passed through the slot 22 of the slidable sleeve 23.

Positioned within the open end of the base is a retaining member 24, having the recesses 25, 26 and 27 and the aligned openings 28, 29.

An elongated flat arm 29 is introduced in the slot 26 and frictionally maintained therein, and a similar elongated flat arm 30 is frictionally maintained in the slot 27. These two arms are formed from one piece bent as shown in Figure 9.

An elongated flat clamping arm 31 having the curved terminal 32 passes through the slot 27 of

the retaining member 24, and is pivotally attached thereto by the pin 33 passed through the holes 28, 28 and holes in two downwardly extended ears 34, 34 of the arm 31.

A resilient spring member 35 having the recess 36 and the upwardly extended terminal 37 is frictionally held within the retaining member 24 by inserting the arms 38, 38 within the recesses 25 and 26. The terminal 37 of the spring is so positioned that in normal position it presses upwardly against the end 32 of the clamping arm 31 with such force as to cause the arm 31 to have a pressure abutment against the upper faces of the arms 29 and 30 as shown particularly, by the full lines in Figure 4.

The pressure abutment between the clamping arm and the fixed arms may be accomplished by other constructions, and by the use of other forms of springs such as coil springs.

The operation of my device is as follows:—

The sleeve 23 is moved outwardly and the arm 19, is shown in 19' in Figure 2. Pressure is then exerted upon the member 32 causing the clamping arm 31 to assume the position 31' as shown in Figures 2 and 4. A strand of hair is then given a few turns around the arms 29 and 30 and the pressure released from the member 32, thus allowing the arm 31 to abut upon the thus wound hair with sufficient force to hold it in place. The entire device is now revolved thus winding the hair around the arms 29, 30 and 31. When the entire strand is thus wound or wrapped around the arms, lower arm 19 is moved into the position shown in Figure 4, and the sleeve 23 moved inwardly into the position shown in Figures 1, 2 35 and 3. The sleeve thus acts to force the arm 19 against the wound hair, holding it in compressed condition free from unwrapping and at the same time prevents the device from slipping from its operative position.

The modified form of my device shown in Figure 10 is the same as that previously described except that the two arms 29 and 30 are replaced by a single arm 39 passing through a centrally positioned slot in the retaining member 24 and 45 a suitable spring member 40 is also positioned therein. I prefer to employ a plurality of such arms as they produce a somewhat more effective and attractive curl.

It will thus be seen that my invention presents a simple and effective device adapted for curling hair.

I do not limit myself to the particular size, shape, number or arrangement of parts as particularly disclosed and described as these are 55

given simply as a means for clearly describing the device of my invention.

What I claim is:—

1. In a hair curling device, in combination, a supporting member, a retaining member, a fixed arm carried by said retaining member, a clamping arm pivotally carried by said retaining member and capable of abutment upon said fixed arm, resilient means adapted to cause abutment between said clamping arm and said fixed arm in normal position, means whereby said clamping arm may be removed from abutment upon said fixed arm, a locking arm pivotally carried by said supporting member and a member carried by said locking arm capable of retaining said locking arm in spaced practically parallel position with said fixed arm.

2. In a hair curling device, in combination, a supporting member, a retaining member, a plurality of fixed arms carried by said retaining member, a clamping arm pivotally carried by said retaining member and capable of abutment upon said fixed arms, resilient means adapted to cause abutment between said clamping arm and said fixed arms in normal position, means whereby said clamping arm may be removed from abutment upon said fixed arms, a locking arm pivotally carried by said supporting member and a member carried by said locking arm capable of retaining said locking arm in spaced practically parallel position with said fixed arms.

3. In a hair curling device, in combination, a supporting member, a retaining member, a fixed arm carried by said retaining member, a clamping arm pivotally carried by said retaining member and capable of abutment upon said fixed arm, resilient means adapted to cause abutment between said clamping arm and said fixed arm in normal position, means whereby said clamping arm may be removed from abutment upon said fixed arm, a locking arm pivotally carried by said supporting member and a sleeve slidably carried by said locking arm capable of encompassing said fixed arm and said clamping arm and maintaining them in practically parallel position with said locking arm.

4. In a hair curling device, in combination, a supporting member, a retaining member, a plurality of fixed arms carried by said retaining member, a clamping arm pivotally carried by said retaining member and capable of abutment upon said fixed arms, resilient means adapted to cause abutment between said clamping arm and said fixed arms in normal position, means whereby said clamping arm may be removed from abutment upon said fixed arms, a locking arm pivotally carried by said supporting member and a sleeve slidably carried by said locking arm capable of encompassing said fixed arms and said clamping arm and maintaining them in practically parallel position with said locking arm.

5. In a hair curling device in combination, a retaining member, a fixed arm carried by said retaining member, a clamping arm pivotally carried by said retaining member and having a curved extremity, a resilient member abutting upon said extremity and adapted to cause abutment between the extended portion of said clamping arm and said fixed arm in normal position, a locking arm and means adapted to maintain said locking arm in spaced practically parallel position with said fixed arm.

6. In a hair curling device, in combination, a retaining member, a plurality of fixed arms carried by said retaining member, a clamping arm

pivotally carried by said retaining member and having a curved extremity, a resilient member abutting upon said extremity and adapted to cause abutment between the extended portion of said clamping arm and said fixed arms in normal position, a locking arm and means adapted to maintain said locking arm in spaced practically parallel position with said fixed arms.

7. In a hair curling device, in combination, a retaining member, a fixed arm carried by said retaining member, a clamping arm pivotally carried by said retaining member and having a curved extremity, a flat resilient member carried by said retaining member and abutting upon said extremity thus causing abutment between the extended portion of said clamping arm and said fixed arm in normal position, a locking arm and means adapted to maintain said locking arm in spaced practically parallel position with said fixed arm.

8. In a hair curling device, in combination, a retaining member, a plurality of fixed arms carried by said retaining member, a clamping arm pivotally carried by said retaining member and having a curved extremity, a flat resilient member carried by said retaining member and abutting upon said extremity, this causing abutment between the extended portion of said clamping arm and said fixed arms in normal position, a locking arm and means adapted to maintain said locking arm in spaced practically parallel position with said fixed arm.

9. In a hair curling device, in combination, a supporting member, a retaining member, a fixed arm carried by said retaining member, a clamping arm pivotally carried by said retaining member and having a curved extremity, a flat resilient member carried by retaining member and abutting upon said extremity, thus causing abutment between the extended portion of said clamping arm and said fixed arm in normal position, a locking arm pivotally carried by said supporting member and means adapted to maintain said locking arm in spaced practically parallel position with said fixed arm.

10. In a hair curling device, in combination, a supporting member, a retaining member, a plurality of fixed arms carried by said retaining member, a clamping arm pivotally carried by said retaining member and having a curved extremity, a flat resilient member carried by said retaining member and abutting upon said extremity, thus causing abutment between the extended portion of said clamping arm and said fixed arms in normal position, a locking arm pivotally carried by said supporting member and means adapted to maintain said locking arm in spaced practically parallel position with said fixed arms.

11. In a hair curling device, in combination, a retaining member, a fixed arm carried by said retaining member, a clamping arm pivotally carried by said retaining member and having a curved extremity, a flat resilient member carried by said retaining member and abutting upon said extremity thus causing abutment between the extended portion of said clamping arm and said fixed arm in normal position, a locking arm, and means carried by said locking arm adapted to maintain said locking arm in spaced practically parallel position with said fixed arm.

12. In a hair curling device, in combination, a retaining member, a plurality of fixed arms carried by said retaining member, a clamping arm pivotally carried by said retaining member and having a curved extremity, a flat resilient mem-

ber carried by said retaining member and abutting upon said extremity, thus causing abutment between the extended portion of said clamping arm and said fixed arms in normal position, a locking arm and means carried by said locking arm adapted to maintain said locking arm in spaced practically parallel position with said fixed arms.

13. In a hair curling device, in combination, a supporting member, a retaining member, a fixed arm carried by said retaining member, a clamping arm pivotally carried by said retaining member and having a curved extremity, a flat resilient member carried by said retaining member and abutting upon said extremity, thus causing abutment between the extended portion of said clamping arm and said fixed arm in normal position, a locking arm pivotally carried by said supporting

member and means carried by said locking arm adapted to maintain said locking arm in spaced practically parallel position with said fixed arm.

14. In a hair curling device, in combination, a supporting member, a retaining member, a plurality of fixed arms carried by said retaining member, a clamping arm pivotally carried by said retaining member and having a curved extremity, a flat resilient member carried by said retaining member and abutting upon said extremity, thus causing abutment between the extended portion of said clamping arm and said fixed arms in normal position, a locking arm pivotally carried by said supporting member, and means carried by said locking arm adapted to maintain said locking arm in spaced practically parallel position with said fixed arms.
